UNITED STATES PATENT OFFICE.

CHARLES W. DAKE, OF CHICAGO, ILLINOIS, ASSIGNOR TO PYLE-NATIONAL ELECTRIC HEADLIGHT COMPANY, OF CHICAGO, ILLINOIS, A CORPORATION OF NEW JERSEY.

INCANDESCENT ELECTRIC HEADLIGHT.

1,098,317.

Specification of Letters Patent. Patented May 26, 1914.

Application filed June 17, 1912. Serial No. 704,916.

To all whom it may concern:

Be it known that I, CHARLES W. DAKE, a citizen of the United States, residing at Chicago, in the county of Cook and State of Illinois, have invented a certain new and useful Improvement in Incandescent Electric Headlights, of which the following is a specification.

My invention relates to incandescent electric headlights for locomotives and the like.

It is illustrated somewhat diagrammatically in the accompanying drawings, where-in—

Figure 1 is a longitudinal section with parts shown in full lines; Fig. 2 is a front view of the lamp.

Like parts are indicated by the same letters in all the figures.

A is the base, B the body and C the back of a reflector casing which contains the headlight reflector D suitably mounted on the standard D¹ and the support D². At the front end of the casing is mounted the tubular projection E carrying the glass E¹. This projection is mounted in any desired manner so as to be removable or hinged or otherwise manipulated to permit access to the interior of the casing and reflector.

F, F are a series of brackets mounted at G, G in the forward rim of the reflector casing. Each bracket carries an incandescent lamp J and a lamp reflector K.

I do not wish to be limited as to the form or size or shape of the headlight reflector or the lamp reflectors or the lamps. In the form in which I have illustrated my invention it presents a parabolic reflector properly placed in the casing and a series of incandescent lamps arranged beyond the reflector and extending inwardly over the edge thereof. These lamps are associated each with a lamp reflector which tends to throw the light of such incandescent lamp down into the body of the headlight reflector. Obviously the curves and surfaces will be so related and adjusted and the lamp so positioned as to get that particular result desired. It is obviously possible by varying the arrangement to get a more or less concentrated pencil of light. These incandescent lamps are coupled in multiple so that when one gives out others are undisturbed.

By utilizing the lamp reflectors the lamps can be placed at the outer rim of the headlight reflector, thus leaving a very large free space in front of the headlight reflector. This free space is of a diameter measured by the distance between the innermost edges of the opposed lamp reflectors for the outer portion of the incandescent lamp bulb is negligible as a light interrupting medium. The lamps and the lamp reflectors can be adjusted or removed and others substituted without difficulty by temporarily removing the tube E or the glass which covers its outer end. This arrangement of the incandescent lamp permits a very large number of them to be used. They project inwardly toward the axis of the light reflector and their non-luminous portions are entirely outside of the path of the light forwardly directed by the headlight reflector.

I claim:

1. An electric headlight comprising a bowl-shaped reflector with a plurality of incandescent electric lights grouped about the outer edge of said reflector projecting inwardly into the field thereof but inclined away from the focal point, the bases of said lamps being located outside of the field of the reflector, separate reflecting surfaces one for each lamp located about the periphery of the reflector and adapted to direct the rays from each lamp toward the center of the reflector.

2. An electric headlight comprising a bowl-shaped reflector with a plurality of incandescent electric lights grouped about the outer edge of said reflector projecting inwardly into the field thereof but inclined away from the focal point, the bases of said lamps being located outside of the field of the reflector, separate reflecting surfaces one for each lamp located about the periphery of the reflector located partially within the field thereof and adapted to direct the rays from each lamp toward the center of the reflector.

Signed at Chicago, Illinois, this 10th day of June, 1912.

CHARLES W. DAKE.
